UNITED STATES PATENT OFFICE

JOHN E. RIGALI, OF CHICAGO, ILLINOIS, ASSIGNOR TO DAPRATO STATUARY COMPANY,
OF CHICAGO, ILLINOIS, A CORPORATION OF ILLINOIS

SPEAKER UNIT AND SUPPORT THEREFOR

Application filed November 21, 1930. Serial No. 497,088.

The invention has reference to speaker units employed in connection with sound amplifying systems, radio receiving circuits and similar devices and the general aim of 5 the present invention is to provide a housing for such a unit and means for supporting said housing, which elements are pleasing and ornamental in appearance and are arranged to permit of adjustment of the housing to 10 meet the acoustic requirements of the auditorium in which the device is used.

An object of the invention is to provide a new and improved means for supporting the speaker unit of a sound amplifying system 15 which is capable of substantially universal adjustment.

More specifically stated, an object of the present invention resides in the provision of a housing for a loud speaker unit and a support 20 for said housing, which housing and support are pleasingly ornamental in appearance, preferably in conformity with the decorative scheme of the hall or auditorium in which the device is used, said housing being substantially 25 in the form of a sphere and said support having a socket therein to receive said sphere whereby a substantially universal adjustment of the housing may be attained.

30 Other objects and advantages will become apparent from the following description and in the accompanying drawings, in which:

Figure 1 is a front elevation of a mounting for a speaker unit embodying the features 35 of the present invention.

Fig. 2 is a side elevation thereof slightly in perspective.

Fig. 3 is a central transverse section of the device taken substantially on the line 3—3 of 40 Fig. 2.

Fig. 4 is a fragmentary front elevation of a modified form of the invention.

In describing the invention, reference is had to the drawings in which I have shown 45 a housing for a speaker unit and a support for said housing. It will be seen that the housing and support embody a highly decorative and ornamental design but it will be understood that this design, with the exception 50 of certain features of construction, forms

no part of the present invention and may be changed, modified, or altered as the manufacturer may see fit to produce an assembly which, in appearance, is entirely in harmony with the surroundings in which the device 55 is to be mounted.

With particular reference to Figs. 1 and 2, 10 designates generally the support and 11 the housing of the assembly. The support 10 comprises a base portion 12 having a pair of spaced members 13 extending therefrom and the ornamentation of the support is such as to embody this construction or the equivalent thereof. Thus, in the present instance, the ornamentation is in the form of a winged head, that is to say, a head (comprising the base 12), from either side of which wings (constituting the members 13) project obliquely upwardly. This support may have a flat back which is not clearly illustrated but would be located substantially at the position designated by the numeral 14. The back is arranged to abut against a wall or other vertical surface to which the support 10 is to be secured in any suitable manner (not shown). The top of the base 12 and the inner opposed portions of the members 13 adjacent the base are arcuately recessed, as at 15 (Fig. 3), to present an upwardly opening socket of spherical contour. 80

The mechanical parts of the speaker unit which have been diagrammatically illustrated at 16 (Fig. 3) are entirely enclosed within the housing 11. This housing is, in this embodiment, substantially in the shape of a sphere which has the same radius of curvature as the radius of the recessed portion 15 of the support. One part of the sphere is cut-away to provide an open front face 17 constituting a sound emission opening, which opening is closed in a customary manner by a screen 18 or the like. At a suitable point, which preferably is diametrically opposed from the open front face, the casing is divided to provide a removable portion 19. This construction allows access to the interior of the casing for repair or adjustment of the mechanical parts of the speaker, the removable portion 19 being normally held in place by fastening devices 20 of any suitable char- 85 90 95 100

acter. Externally the housing 11 is ornamented to conform and harmonize with the decorative scheme of the support 10, thus providing a structure which is pleasing in appearance.

It will be evident from the foregoing that the snug complementary interfitting arrangement of the parts allows the housing to be turned at substantially any angle and to be supported in such position by gravity whereby the open face of the housing may be adjusted to direct the sound as desired. Consequently, the device may be mounted at any convenient point in the auditorium and then adjusted to secure a desired direction of sound, as well as to obtain the fullest advantage of the acoustic properties of the surroundings.

The modified form of structure shown in Fig. 4 is adapted for use where the desired manner of mounting the support does not permit the housing to be supported in the recess by gravity. In other words, it will sometimes be necessary to mount the support near or on the ceiling of the auditorium, or in some other position from which the sound is directed downwardly. In this form of structure, the spaced members 13 of the support depend from the base 12, the parts being shaped, as before, to define the spherically contoured recess. The spherical housing 11 is supported in the recess by such means as opposed trunnions 22 carried by the depending members 13. Consequently, when the assembly is properly mounted, the housing may be pivotally adjustable relative to the support through a wide arc to dispose the open face of the housing in any desired position.

It will be apparent from the foregoing that a novel speaker unit and support therefor has been provided which is capable of being substantially universally adjusted to face the sound emission aperture of the speaker casing in any desired direction thereby enabling the operator to instantly adjust the device to meet the requirements of the particular locality in which it is mounted. Moreover, the present device is highly ornamental in appearance and the ornamentation thereof may be of a type which harmonizes with the decorative scheme of the auditorium. Hence, the present device is well adapted to be used in churches and similar buildings without detracting from the appearance thereof.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling with the spirit and scope of

the invention as expressed in the appended claims.

I claim as my invention:

1. A supporting device for the speaker unit of a sound amplifying system comprising, in combination, an ornamental base having members extending therefrom, said base and said members being continuously recessed to form a spherically contoured socket, and a spherically shaped housing for the mechanical parts of a speaker unit positioned in said recess. 70 75

2. A supporting device for the speaker unit of a sound amplifying system having, in combination, a support comprising a base having a pair of members diverging therefrom, said base and said members being fashioned to define a spherically contoured recess therebetween and a housing for the mechanical parts of a unit, said housing being substantially spherical in shape to fit within said recess in any relative position of adjustment, and having a sound emission opening therein adjustably directed by relative movement of said housing and support. 80 85 90

3. A supporting device for the speaker unit of a sound amplifying system comprising, in combination, an ornamental support including spaced members extending therefrom, said members on the intermediate portion of said support being recessed to form a spherically contoured recess, a spherically shaped housing for the mechanical parts of a unit positioned in said recess, and means for pivotally connecting said housing to said members for swinging adjustment relative to said support. 95 100 105

4. In a speaker unit, the combination of a substantially spherically shaped ornamented housing, and a supporting member in the form of an ornamental figure having a complementary recess therein to receive and support said housing for substantially universal adjustment. 110

In testimony whereof, I have hereunto affixed my signature.

JOHN E. RIGALI.
